ELECTRIC CONNECTOR PLUG ASSEMBLING
MACHINERussell J. Turner, Butler, Pa., assignor to Belden
Manufacturing Company, Chicago, Ill., a cor-
poration of Illinois

Application January 26, 1935, Serial No. 3,673

11 Claims. (Cl. 29—84)

This invention relates to mechanism for assembling electrical connector plugs and more particularly to a device for assembling the prongs of a male type electrical connector plug with a body of resilient material such as rubber, which is pre-formed with passageways for receiving and positioning the contact prongs.

The main object of the invention is to provide mechanism for assembling a body part and contact prongs of the type referred to conveniently, rapidly and inexpensively so as to facilitate the production of resilient rubber or like connector plugs on a practical commercial basis.

Other objects and advantages of the invention will be understood by reference to the following specification and accompanying drawings (two sheets), wherein there is illustrated mechanism for the purpose indicated according to one simple form of the invention.

20 In the drawings—

Fig. 1 is a longitudinal section through the axis and prongs of an electrical connector plug, the assembling of which is the object of the mechanism herein disclosed;

25 Fig. 2 is a side elevation of a simple form of mechanism for the purpose indicated;

Fig. 3 is a perspective of a plug body holding portion of the mechanism; and

30 Figs. 4, 5, 6 and 7 are fragmentary plans respectively illustrating successive steps or positions of the mechanism in the operation of assembling a connector plug of the type shown in Fig. 1.

Referring now to the drawings, the connector plug illustrated in Fig. 1 comprises a body 10 which is formed of resilient material, preferably rubber or rubber compound, which is soft enough to be distortable and resilient enough to have the property of resuming its normal pre-formed shape (or at least as nearly resuming the same as possible) from any distorted position or condition.

40 Electrical contact prongs are designated 11, 11. They are provided near their outer ends with holes 12, 12, substantially in accord with more or less standardized practice. The inner end portions 13, 13 of the contact prongs are positioned in the body 10 in recesses 14, 14 which are formed in the body during the molding thereof. The recesses 14, 14 do not extend entirely through the plug but terminate within the plug body so as 45 to form seats 15, 15 adapted to engage the inner ends of the prongs to prevent the prongs from being pushed rearwardly through the plug body.

50 The prong receiving recesses 14, 14 open to the front end of the plug body and the opposite or rear end of the latter is provided with a recess

or passage 16 which is designed to receive the end portion of a duplex conductor. The wires 17, 17 of said duplex conductor are respectively connected, as indicated at 18, 18 to the inner end portions of the contact prongs. One mode of connecting the wires 17, 17 to the contact prongs may consist in projecting end portions of the bared wires through suitable openings in the inner end portions of the contact prongs and soldering the projecting end portions down against the outer 10 faces of the rear ends of the contact prongs as indicated. The passage 16 communicates with the prong receiving recesses or passages 14 through the agency of holes or openings 19, 19.

It will be evident from a consideration of the 15 structure above explained that the conductor wires must be connected to the contact prongs 11, 11 before the latter are assembled with the plug body. This circumstance makes it desirable, if not actually necessary, to insert the contact 20 prongs from the rear of the connector plug body by passing the prongs forwardly through the openings 16, 19 and 14.

The mechanism herein disclosed effects assembly of the described connector in the manner indicated and it comprises a base or bed plate 20 supported on suitable end frames or posts 21, 21. A guide block 22 is rigidly secured to the bed plate base 20 by any suitable means, for example, bolts, as indicated. The guide post 22 is provided with 25 an aperture 23 extending therethrough and slidably receiving a rod or bar 24. In this instance, the rod 24 is shown as being of circular cross section and the aperture 23 consists of a hole bored to slidably receive such rod. The rod is 30 adapted to be reciprocated through the guide post 22 by means of an operating handle 25 which passes through a slot in the base and is pivoted adjacent its lower end as indicated at 26 on a bracket 27 depending from and securely attached 35 to the base plate 20 in any suitable manner, for example, by means of one or more bolts as indicated. The rod 24 is slotted as indicated at 28 adjacent its outer end to permit the handle 25 to be passed therethrough and the handle is 40 preferably provided with curved operating edges such as indicated at 29, 29, where it rests within the slot 28 of the slidable rod 24. It will be evident that by rocking the handle or lever 25 on its pivot, the bar 24 will be reciprocated in the guide 45 block 22.

The other end of the reciprocating rod 24 is provided with a built-up head 30 which carries a number of transversely spaced pivot pins 31. The latter project upwardly from the top sur- 50

face 32 of the head 30, said top surface being preferably substantially flat, or at least provided with co-planar bearing surfaces around the respective pivot pins 31. A pair of fingers 33, 33 are pivoted adjacent their rear ends on the respective pivot pins 31, 31 through the agency of suitably apertured enlargements 34, as best indicated in Figs. 4 to 7 inclusive. Arms or extensions 35, 35 are rigidly connected to, and in this instance integrally formed with, the fingers 33, 33 and said extensions at their rear or free ends are provided with upstanding pins 36, 36 which are designed to engage the cam surfaces 37, 37 of a cam bar or plate 38. The latter is carried by the guide post 22, being secured to the top thereof by such means as bolts 39. A suitable spring such as indicated at 40 connected at its opposite ends and stretched between the rear end portions of the finger extensions 35, 35 serves to yieldingly hold the cam pins 36, 36 in operative engagement with the cam edges 37, 37.

The fingers 33, 33 are provided near their forward free ends with latterly outwardly projecting elements 41, 41 which are preferably provided with small lip portions 42, 42 so as to form retainers for contact prongs which are adapted to be secured to the fingers by the insertion of the pin elements 41, 41 through the outer end openings 12, 12 of the contact prongs. A holder 43 is secured to the forward end of the base plate by any suitable means and it is provided in its upper end with a recess or socket 44, the cross-sectional shape of which approximates the shape of the plug body which the holder is intended to receive. The depth of the socket 44 is preferably slightly greater than one-half the diameter of the plug body so that the plug body will be adequately supported during the assembling operations, which will presently be described. The front wall 45 of the socket 44 is provided with openings such as indicated at 46, 46 which are approximately aligned with the contact prong receiving recesses 14, 14 of the plug body.

The first step in assembling a connector plug 45 of the type shown in Fig. 1 is to position the body 10 in the socket of the holder 43, as indicated in Fig. 4. The next step is to effect movement of the rod 24 and fingers 33 forwardly. The cam surfaces of the cam plate 38 are so shaped that 50 the free ends of the fingers 33 will be steered into the prong receiving recesses 14, 14 as an incident to the forward reciprocating movement thereof. The pin elements 41, 41 of the fingers 33 are preferably provided with beveled or inclined 55 front faces 47, 47 so as to facilitate the forward movement of the fingers into and through the prong receiving recesses 14, 14. As the fingers progress into the recesses 14, 14, they are caused to move towards each other by appropriate shaping of the cam 38 so that the free ends of the fingers will enter and pass through the conductor receiving opening 16, so that in the extreme forward position of the fingers 33, 33, they will occupy the location indicated in Fig. 5 with respect 60 to the connector plug body 10.

The next step in the operation of assembling the prongs with the plug body is to attach connector prongs 11, 11 with the respective wires 17, 17 attached thereto in the manner indicated, by 65 engaging the finger pin means 41, 41 with the openings 12, 12 in the contact prongs. It will be evident by inspection of Fig. 5 that the lips 42, 42 serve the purpose of preventing lateral displacement of the contact prongs from the hooks 70 or pins 41.

The contact prongs with wires attached being properly applied to the projecting ends of the fingers, the next step is to effect return or rearward movement of the fingers 33, 33 through the agency of the operating lever handle, with the result that the contact prongs 11, 11 are pulled into and through the plug body as indicated in Figs. 6 and 7. Of course it will be apparent that the cam 38 is so shaped as to cause the free ends of the fingers to follow the course of the respective openings through which the prongs are pulled, it being also understood that due to the resiliency of the body material, the body may be and is distorted (without destroying the resiliency thereof) as an incident to the movement of 13 the fingers or fingers and prongs through the plug body. The fingers 33, 33 are shaped approximately as shown in the drawings to reduce to the greatest extent feasible the necessary distortion of the plug body, and to facilitate movement of 20 the fingers through the body, they are preferably finished with smooth and more or less polished surfaces. Sharp corners on the fingers are preferably avoided.

When the prongs are pulled through the body 25 to the position in which they are illustrated in Fig. 7, the cam 38 operates to effect such inward movement of the free ends of the fingers 33, 33 as to disengage the pin portions 41, 41 from the prong apertures 12, 12 so as to free the plug body 30 and prongs from the operating mechanism of the assembling device. The plug body with the prongs seated therein may now be removed from the holder and it is ready for its intended use, except for the seating of the inner ends of the 35 prongs against the bottoms 15, 15 of the prong positioning recesses, which is readily accomplished by applying the required amount of pressure to the outer ends of the prongs so as to cause the latter to move rearwardly in the body. 40

The passages 16, 19 and 14 constitute sinuous or tortuous passageways through which the straight contact prongs are pulled, this being permitted by reason of the distortability of the plug body. The opening 16 being centrally disposed in the rear end of the plug body, receives an end portion of the duplex conductor, as clearly shown in Figs. 1 and 7, and in some instances, the duplex conductor may be built up by means of filler cords or the like to form a substantially round 50 duplex conductor which may conveniently be covered with a sheath of rubber insulation. In such instances, the passage 16 may be of such size as to snugly fit the conductor and the prong positioning recesses 14, 14 are also preferably of 55 such size that the prong will be firmly held without material rocking or wobbling movement.

The described mechanism is of very simple form and construction but embodies a practicable form of mechanism required for the purpose 60 illustrated. Changes may of course be made without departing from the spirit of the invention, the scope of which may be determined by reference to the following claims, the same being construed as broadly as possible consistent 65 with the state of the art.

I claim:

1. In a machine for assembling an electrical contact prong with an electrical connector plug body having a sinuous passageway extending 70 therethrough for the reception of the contact prong, the combination of a base, a holder on said base for a connector plug body, a finger carried by said base so as to be movable longitudinally through the sinuous passageway in a plug body 75

in said holder and also laterally so as to be adapted to follow said sinuous passageway, means for actuating said finger so as to move the same forwardly and then rearwardly through said passageway, means for causing a portion of said finger to move laterally during its movement through said opening to approximately follow the course of said passageway, and means carried by said finger for engaging a contact prong during 5 the return or rearward movement of the finger for pulling such prong into said body.

2. In a machine for assembling an electrical contact prong with an electrical connector plug body having a tortuous passageway extending therethrough for the reception of the contact prong, the combination of a base, a holder on said base for a connector plug body, a member mounted on said base for sliding reciprocatory movement toward and from said holder, a finger 10 pivotally mounted on said member and adapted to be projected through and withdrawn from the passageway in a connector plug body in said holder as an incident to the reciprocatory movement of said member, means carried by said finger for engaging a contact prong during the withdrawal of the finger for pulling said prong into said passageway, the pivotal mounting of said finger serving to permit lateral rocking movement of the finger whereby the latter is adapted 15 to more or less follow the course of said tortuous passageway, means for effecting said reciprocatory movement of said member and finger, and cam means for causing portions of said fingers to approximately follow the course of said tortuous passageway.

3. In a machine for assembling an electrical contact prong with an electrical connector plug body made of resilient material and having a sinuous passageway formed therein, a base, a holder for positioning a plug body in predetermined relation to said base, a substantially rigid finger mounted on said base for reciprocating movement toward and from said holder and for lateral movement simultaneously with said reciprocating movement, means for effecting said reciprocating movement of the finger whereby the finger is adapted to be moved through and withdrawn from the passageway in a plug body in said holder, means for simultaneously effecting 20 said lateral movement of the finger so as to cause the leading end portion of the finger to approximately follow the course of the passageway, and means carried by said finger for engaging a contact prong during the withdrawal of the finger from said passageway for pulling such contact prong into the body, the resiliency of the plug body serving to permit such distortion of a portion of the plug body by the finger and by the prong as may be required for the movement of 25 the finger and prong in the passageway.

4. In a machine for assembling an electrical contact prong with an electrical connector plug body having a sinuous passageway extending therethrough for the reception of the contact prong, the combination of a base, a holder on said base for a connector plug body, a finger carried by said base so as to be movable longitudinally through the sinuous passageway in a plug body in said holder and also laterally so as to be 30 adapted to follow said sinuous passageway, lever means for actuating said finger so as to move the same forwardly and then rearwardly through said passageway, cam means operative as an incident to the longitudinal movement of said finger to cause a portion of said finger to move laterally

during its movement through said opening to approximately follow the course of said passageway, and means carried by said finger for engaging a contact prong during the return or rearward movement of the finger for pulling such prong into said body. 5

5. In a machine for assembling a pair of electrical contact prongs with an electrical connector plug body having a pair of sinuous passageways for receiving said prongs, a base, a holder on the base for positioning a connector plug body, a member mounted on the base for reciprocatory movement toward and from said holder, a pair of fingers rockably mounted on said member and adapted to be reciprocated therewith so as to be projected through and withdrawn from the passageways in a connector plug body in said holder, and a pair of opposed cams for rocking said fingers to thereby effect lateral movement of the free end portions thereof in approximate conformity to the courses of the prong receiving passageways. 10

6. In a machine for assembling a pair of electrical contact prongs with an electrical connector plug body having a pair of sinuous passageways for receiving said prongs, a base, a holder on the base for positioning a connector plug body, a member mounted on the base for reciprocatory movement toward and from said holder, a pair of fingers rockably mounted on said member and adapted to be reciprocated therewith so as to be projected through and withdrawn from the passageways in a connector plug body in said holder, and a pair of opposed stationary cams for rocking said fingers as an incident to the reciprocating movement of said fingers to thereby effect lateral movement of the free end portions thereof in approximate conformity to the courses of the prong receiving passageways. 15

7. In a machine for assembling a pair of electrical contact prongs with an electrical connector plug body having a pair of sinuous passageways for receiving said prongs, a base, a holder on the base for positioning a connector plug body, a member mounted on the base for reciprocatory movement toward and from said holder, a pair of fingers rockably mounted on said member and adapted to be reciprocated therewith so as to be projected through and withdrawn from the passageways in a connector plug body in said holder, a pair of opposed stationary cams for simultaneously but oppositely rocking said fingers as an incident to the reciprocating movement of said fingers to thereby effect lateral movement of the free end portions thereof in approximate conformity to the courses of the prong receiving passageways, and means for maintaining cooperative relationship between said fingers and cams. 20

8. In a machine for assembling a pair of electrical contact prongs with an electrical connector plug body having a pair of sinuous passageways for receiving said prongs, a base, a holder on the base for positioning a connector plug body, a member mounted on the base for reciprocatory movement toward and from said holder, a pair of fingers pivotally mounted adjacent their rear ends on said member and adapted to be reciprocated therewith so as to be projected through and withdrawn from the passageways in a connector body in said holder, arms connected to said fingers and extending rearwardly therefrom beyond the pivots thereof, a pair of opposed cams acting on said arms as an incident to the reciprocating movement thereof to effect rocking of the forward end portions of said fingers in approxi- 25 30 35 40 45 50 55 60 65 70 75

mate conformity to the courses of the passageways during the movement of the fingers through the passageways.

9. In a machine for assembling a pair of electrical contact prongs with an electrical connector plug body having a pair of sinuous passageways for receiving said prongs, a base, a holder on the base for positioning a connector plug body, a member mounted on the base for reciprocatory movement toward and from said holder, a pair of fingers pivotally mounted adjacent their rear ends on said member and adapted to be reciprocated therewith so as to be projected through and withdrawn from the passageways in a connector body in said holder, arms connected to said fingers and extending rearwardly therefrom and beyond the pivots thereof, a part having a pair of opposed cams formed on its opposite edges, said part being located intermediate said arms and the cams and acting on said arms as an incident to the reciprocating movement thereof to effect rocking of the forward end portions of said fingers in approximate conformity to the courses of the passageways during the movement of the fingers through the passageways.
10. In a machine for assembling a pair of electrical contact prongs with an electrical connector plug body having a pair of sinuous passageways for receiving said prongs, a base, a holder on the base comprising a stationary part having a socket

formed therein for receiving, positioning and supporting a connector plug body, a member mounted on the base for reciprocatory movement toward and from said holder, a pair of fingers rockably mounted on said member and adapted to be reciprocated therewith so as to be projected through and withdrawn from the passageways in a connector plug body in said holder, and a pair of opposed cams for rocking said fingers to thereby effect lateral movement of the free end portions thereof in approximate conformity to the courses of the prong receiving passageways.

11. In a machine for assembling a pair of electrical contact prongs with an electrical connector plug body having a pair of sinuous passageways for receiving said prongs, a base, a holder on the base for positioning a connector plug body, a member mounted on the base for reciprocatory movement toward and from said holder, a pair of fingers rockably mounted on said member and adapted to be reciprocated therewith so as to be projected through and withdrawn from the passageways in a connector plug body in said holder, and means for rocking said fingers to thereby effect lateral movement of the free end portions thereof in approximate conformity to the courses of the prong receiving passageways.

RUSSELL J. TURNER. 30
